UNITED STATES PATENT OFFICE.

ROBERT C. LEGAT, OF NEW BRITAIN, CONNECTICUT, ASSIGNOR TO G. E. PRENTICE MANUFACTURING COMPANY, OF NEW BRITAIN, CONNECTICUT, A CORPORATION OF CONNECTICUT.

KEY CASE.

Application filed July 12, 1927. Serial No. 205,141.

This invention relates to key cases of a type now commonly used for carrying a plurality of keys so as to prevent their loss and to protect the pocket of the user from excessive wear.

Among the objects of the invention are to provide a simple and practical structure of this character which may be quickly, easily and cheaply made and to provide a key retainer for such cases so designed that the keys are freely movable in substantially all directions with respect to the case, thus permitting the keys to be used in practically any position without requiring that they be removed from the case.

Other objects and advantages will be pointed out in the claims and will be apparent from a description of one embodiment of the invention in the following specification when read with the accompanying drawings; in which

Fig. 1 is an elevation of the complete case in open position;

Fig. 2 is a section on the line 2—2 of Fig. 1;

Fig. 3 is a section similar to Fig. 2, but showing the parts during the process of construction; and

Fig. 4 is an elevation of a key-holding member.

As an example of the use of my improved key-retaining device I have herein illustrated a case which may be constructed in any usual manner and which comprises a piece of leather or other flexible material folded along lines 2 and 3 and thus providing a central portion or back 1 and the side flaps 4 and 5. The side flaps are normally folded over onto the central portion or back 1 and these flaps may be provided with any usual fastening means, such for example as the two-part snap fastener indicated at 6.

My improved key-retaining device is adapted to form a permanent part of the case and is preferably made of sheet metal, although I contemplate that other materials might possibly be found useful. In constructing this key-retaining device I provide a piece of sheet metal of proper shape, such a piece comprising the attaching member 7 which is adapted to lie flat against the back member 1 of the case and which is secured to the said back member by means of rivets or eyelets 8. The piece of sheet metal is bent

forwardly at the upper edge of the attaching portion 7 and is then bent upwardly again to provide a platform 10 substantially parallel to but spaced forwardly from the plane of the attaching portion 7. The platform 10 is provided with a series of horizontally spaced forwardly directed hollow struck-up substantially hemispherical projections 11, each furnished with a vertically elongate slot 13. In the completed device the metal is again bent at the upper edge of the platform 10 so as to extend rearwardly and downwardly in a curve forming the protecting or enclosing element 14 whose lower edge terminates adjacent to the upper edge of the attaching part 7. The forwardly positioned platform 10 and the rearwardly extending curved element 14 provide between them a cavity 9.

With each of the hemispherical projections 11 I associate an individual key holder, 75 each such key holder preferably comprising an anchor member 16 and a key-engaging member 17. The anchor members may be made, if desired, by a stamping or other convenient operation from sheet metal and 80 each anchor member comprises a head or enlargement 18 which is normally disposed within the cavity 9 between the members 10 and 14. This head 18 is preferably substantially spherical and adapted to cooperate 85 with the hemispherical concavity at the rear of the projection 11 to form a ball and socket joint. Each anchor member is provided with a relatively small neck portion 19 integrally united to the head 18 and projecting forwardly through the slot 13. The 90 forward end of the neck 19 is preferably flattened and enlarged as shown at 20 and furnished with an opening or eyelet 21.

The key-engaging member 17 preferably 95 consists of a length of wire which is bent at its central portion to form a substantially closed loop or eye 22 adapted to engage the opening or eyelet 21. The member 17 also comprises divergent legs 23 and 24 which, 100 at their free ends, are bent to form curved beak-like hooks 25 and 26 which are oppositely directed and which overlap, thus collectively forming a split-loop adapted to receive a key in much the same way as the 105 ordinary split-ring type of key holder. Such a split loop readily receives a key but positively prevents the escape of the key

after it is once properly engaged therewith. In assembling the parts I first pass the forward end 20 of the anchor member forwardly through the slot 13 and then separate the hook members 25 and 26 sufficiently to permit the key-engaging element 17 to be threaded through the opening 21 until the ring or loop 21 engages the opening in the part 20. If desired, the ring 22 may now 10 be subjected to pressure so as completely to close it, although this is not essential.

The above operations are performed while the part 14 occupies the position shown in Fig. 3 and after all the key holders have 15 been assembled in this manner the part 14 is bent downwardly until it occupies the position shown in Fig. 2, thus permanently retaining the holders in position. The attaching member 7 of the key-retaining device 20 may be secured to the back of the casing either before or after the assembly of the parts as above described.

The device thus provided is simple in character, its constituent parts are easy to 25 make and assemble, it is compact and light in weight, and it is very strong and durable. Furthermore, it provides maximum freedom for the keys, since the anchor members 15 may be rotated to any position and may be moved longitudinally in the slots, while the key-engaging members 17 may have a substantially universal movement limited only by contact with the back and top of the case. The result of this arrangement of parts is 30 that when the case is opened and turned to any position, the keys will still hang freely and will not cramp or project rigidly forward or otherwise, and will not tend to get mixed up with each other, and thus the greatest liberty of use of the keys is afforded.

I claim:

1. A key case having a retaining member provided with pivoted connecting members adapted to carry key holders, said retaining member comprising a rigid sheet having an 45 attaching portion and a platform spaced

forwardly from the attaching portion, and a series of substantially hemispherical protuberances formed in said platform, each projection having a diametrical slot mounting one of said connecting members. 50

2. A key case comprising a casing, a retaining member formed of sheet metal and consisting of an attaching portion secured to the casing, a platform spaced forwardly 55 of the upper edge of the attaching portion and arranged substantially parallel thereto, and an enclosing portion spaced behind the platform and terminating adjacent the said upper edge of the attaching portion, a series of spaced, substantially hemispherical protuberances formed in said platform, each protuberance having a diametrical slot, and a plurality of pivoted connecting members 60 adapted to carry key holders, each connecting member having a head retained behind one of said protuberances and cooperating therewith to provide a ball and socket joint. 65

3. A key case comprising a casing, a retaining member formed of sheet metal and 70 consisting of a lower attaching portion, a platform spaced forwardly of the upper edge of the attaching portion and arranged substantially parallel thereto, and an enclosing portion curving rearwardly behind the 75 platform and having its upper edge terminating adjacent the upper edge of the attaching portion, a series of spaced, substantially hemispherical protuberances formed in said platform, each protuberance having a diametrical slot extending transversely of 80 said platform, and a plurality of anchor members adapted to carry key holders, each anchor member having a substantially hemispherical head pivotally mounted behind the platform and seating within one of said protuberances and cooperating therewith to 85 constitute a ball and socket joint.

Signed by me at Berlin, Conn., this first day of July, 1927.

ROBERT C. LEGAT.
